US00D741354S

(12) **United States Design Patent**
Lee et al.

(10) **Patent No.:** US D741,354 S
(45) **Date of Patent:** ** Oct. 20, 2015

(54) **DISPLAY SCREEN WITH GRAPHICAL USER INTERFACE**

(71) Applicant: **LG ELECTRONICS INC.**, Seoul (KR)

(72) Inventors: **Kunsik Lee**, Seoul (KR); **Uniyoung Kim**, Seoul (KR); **Gooryong Kang**, Goyang-si (KR); **Gangseub Lee**, Seoul (KR); **Hyejin Yu**, Yongin-si (KR); **Hyungnam Lee**, Anyang-si (KR)

(73) Assignee: **LG Electronics Inc.**, Seoul (KR)

(**) Term: **14 Years**

(21) Appl. No.: **29/457,797**

(22) Filed: **Jun. 13, 2013**

(30) **Foreign Application Priority Data**

Dec. 14, 2012 (KR) 30-2012-0060588

(51) **LOC (10) Cl.** **14-04**

(52) **U.S. Cl.**

USPC **D14/487**

(58) **Field of Classification Search**

(57) **CLAIM**

The ornamental design for a display screen with graphical user interface, as shown and described.

DESCRIPTION

The FIGURE is a front view of a display screen with graphical user interface showing our design.

The dashed broken lines form no part of the claimed design. The dash-dot broken lines define the bounds of the claimed design and form no part thereof

1 Claim, 1 Drawing Sheet
